UNITED STATES PATENT OFFICE

129,515

DESIGN FOR A BOTTLE

Jacob Payne, Manhasset, N. Y.

Application December 18, 1940, Serial No. 97,430

Term of patent 3½ years

To all whom it may concern:

Be it known that I, Jacob Payne, a subject of Great Britain and residing in the town of Manhasset, in the county of Nassau and State of New York, have invented a new, original, and ornamental Design for Bottles, of which the following is a specification, reference being had to the accompanying drawing, forming part thereof.

Figure 1 is a plan view of a bottle showing my new design; Figure 2 is a front elevational view of the bottle; Figure 3 is a side elevational view of the bottle; Figure 4 is a bottom view of the bottle; Figure 5 is a sectional view taken on the line 5—5 of Figure 2.

I claim:

The ornamental design for a bottle, as shown.

JACOB PAYNE.
